Des. 224,864
Patented Oct. 3, 1972

224,864

HOLDER FOR PAPER ROLLS

August Belz, 13 Seestrasse, 9403 Goldach, Switzerland

Filed June 8, 1970, Ser. No. 23,351

Term of patent 14 years

Int. Cl. D6—06

U.S. Cl. D6—97

FIG. 1

FIG. 2

FIG. 4

FIG. 3

FIG. 5

FIG. 1 is a perspective front view of the holder for paper rolls embodying my new design;

FIG. 2 is a perspective front view of the holder without rolls and with the door open;

FIG. 3 is a perspective rear view of the holder;

FIG. 4 is a top view thereof; and

FIG. 5 is a bottom view thereof.

The broken lines are shown for illustrative purposes only.

I claim:

The ornamental design for a holder for paper rolls, as shown and described.
